United States Patent Office

Des. 178,180
Patented July 3, 1956

178,180

PLAYGROUND STREET CAR

Jack W. Francis and Samuel W. Daugherty,
Oakland, Calif.

Application August 15, 1955, Serial No. 37,441

Term of patent 14 years

(Cl. D34—15)

Des. 178,180

PAGE 2

FIG. 2.

Fig. 3.

Fig. 1 is a top perspective view of a playground street car showing our new design, a portion of the trolley being omitted for convenience of illustration;

Fig. 2 is a side elevational perspective view thereof, both sides being alike; and

Fig. 3 is an end elevational perspective view thereof, both ends being substantially alike.

We claim:

The ornamental design for a playground street car, as shown and described.
